UNITED STATES PATENT OFFICE.

CEDRIC CHIVERS, OF BATH, ENGLAND.

DESIGN FOR A BOOK-EDGE PROTECTOR.

SPECIFICATION forming part of Design No. 35,284, dated November 12, 1901.

Application filed October 5, 1901. Serial No. 77,748. Term of patent 7 years.

To all whom it may concern:

Be it known that I, CEDRIC CHIVERS, a subject of His Majesty the King of Great Britain, residing at Bath, in the county of Somerset, 5 England, have invented and produced a new and original Design for a Book-Edge Protector, of which the following is a specification, reference being made to the accompanying drawing, forming part thereof, in which the 10 figure is a perspective view of the design in question.

As illustrated in the drawing, the leading or material feature of my design consists of the configuration or shape of the protector, 15 which has three sides *a*, forming an incomplete rectangle. Near the sides *a* and substantially parallel thereto and within the incomplete rectangular figure thus formed is a second incomplete rectangular figure formed 20 by the sides *b*. From the upper and lower

of the sides *a* projects a flap *c*, the flaps extending toward each other in a plane at right angles to the plane of the sides *a*. A flat strip-like ornament *e* projects from one of the free ends of a side *a*, and the end of this ornament *e* terminates in a ring-shaped ornament *d*. 25

Having described my invention, what I claim as new, and desire to secure by Letters Patent, is—

The design for a book-edge protector as herein shown and described.

In testimony whereof I have hereunto set my hand in the presence of two subscribing witnesses.

CEDRIC CHIVERS.

Witnesses:

FREDERICK CLIFT,
FREDERICK GEORGE ORGER.
